AUTOMOBILE REAR DECK MOLDING

Arthur Ross, Detroit, Mich., assignor to General Motors
Corporation, Detroit, Mich., a corporation of Delaware

Application October 20, 1954, Serial No. 32,733

Term of patent 7 years

(Cl. D14—6)

Fig.1

Fig.2

Fig. 1 is a rear elevational view of an automobile rear deck molding embodying my new design;

Fig. 2 is a view similar to Fig. 1 but on a larger scale;

Fig. 3 is a top plan view of the molding;

Fig. 4 is a side elevation of the molding; and

Figs. 5, 6, 7 and 8, respectively, are transverse sections showing the cross-sectional configuration of the molding at different locations thereon as indicated in Figs. 2 and 4.

The fragmentary portions of an automobile shown by

means of dot-dash lines are only disclosed for purposes of illustration.

I claim:

The ornamental design for an automobile rear deck molding, substantially as shown and described.
